UNITED STATES PATENT OFFICE.

JONAH WOODRUFF, OF PHILADELPHIA, PENNSYLVANIA.

IMPROVEMENT IN SLEEPING-CARS.

Specification forming part of Letters Patent No. 147,539, dated February 17, 1874; application filed October 14, 1873.

CASE A.

To all whom it may concern:

Be it known that I, JONAH WOODRUFF, of Philadelphia, in the county of Philadelphia and State of Pennsylvania, have invented a new and useful Improvement in Sleeping-Cars; and I do hereby declare the following to be a full, clear, and exact description thereof, reference being had to the accompanying drawing making a part of this specification, in which—

Figure 1 is a view in perspective of a section of my improved sleeping-car, as the same appears when in condition for day service. Fig. 2 is a transverse section of the same with the seats and seat-backs removed, and showing the upper-berth platform, both in position for use as a couch and also in the position it occupies when the car is used as a day car. Fig. 3, by an irregular longitudinal section, further illustrates the same features; and Fig. 4 is a detached view of the upper-berth platform and the appliances connected therewith, by which it is attached to the car and operated.

Like letters of reference indicate like parts in each.

My present invention relates to improvements in the class of sleeping-cars referred to in Letters Patent granted to me July 12, 1870, No. 105,288; and the nature of it consists in the construction and combination of devices by which the upper-berth platform is brought into and held in position for use for night service, and stowed away when the car is used as a day car.

To enable others skilled in the art to make and use my improvement, I will proceed to describe its construction and mode of operation.

The side of the car-body is shown at A, the floor at A', the end frames of the seats at B², and the recesses under the seats, for the reception of bedding, &c., at B¹. The recess in the side of the car-body for the reception of the upper-berth platform is represented at D, and is made as described in the patent above named, except that I prefer to make it only of sufficient depth to receive the upper-berth platform. This upper-berth platform, consist-

ing of two halves, a and a', is more fully represented in Fig. 4, said halves being hinged together, and the outer one being upholstered, as shown, is rigidly fastened to the frames or supports c, as shown, and in such way that the supports shall give a firm bearing along the ends of the half of the platform to which they are attached, thereby the better to hold it in position when elevated, and preferably they project, as shown at c¹, sufficiently far beyond the line of hinging so as to support the adjacent edge of the other or folding half of the platform, as illustrated in Fig. 2, the opposite edge of the folding half resting, when elevated, upon the pins c² attached to the sides of the car at the proper elevation. The supporting-frames c are arranged at the ends of the berth-platform, and are attached by means of a slot, c³, and pin c⁴, to the berth-partition B, in such way that when the berth-platform is stowed away, as shown in Fig. 2, such supporting-frames will be concealed from view by the seat-backs s. The position of the devices referred to, when the car is fitted up for day service, is as illustrated in Fig. 1.

To fit it up for use as a sleeping-car, the seat-backs s, seats s¹, and front panels s³ are folded down, as shown in Fig. 3, onto the floor. The porter, taking hold of the handles e, which are attached to the upholstered face of the berth-platform a for that purpose, draws the berth-platform horizontally out of its recess D, (the slot c³ being long enough to permit of such motion,) as illustrated by dotted lines in Fig. 2, and then swings it upward till it comes in a horizontal position, letting the supports c drop down until the upper end of the slot c³ rests on the pin c⁴, and fastens it in such position by means of the slide c¹, which is attached to the supporting-frame, and which engages a suitable pin on the bracket b', which latter is attached to the partition B. He then unfolds or turns backward toward the sides of the car the folded half a' of the berth-platform till it rests on the supporting-pins c², as already described. This constitutes the upper-berth platform, and the bedding is placed thereon in the usual way, with curtains or other suitable partitions between and in front of the sections.

The lower-berth platform may be of any suitable construction, either that shown in the patent above referred to, or such a one as forms a part of the subject-matter of a separate application filed herewith. To fit it up for day service the operation is simply reversed, and the upper-berth platform being folded together is placed in the recess D, and the seats and seat-backs being raised up gives each section the appearance shown in Fig. 1.

What I claim as my invention, and desire to secure by Letters Patent, is—

The longitudinally-jointed upper-berth plat-

form *a a'*, attached to the pivoted supporting arms *c*, which are placed in suitable position to partially support the upper-berth platform extended as a couch, or to be thrown down behind the seat-backs to serve as guides in placing the folded berth-platforms in the recess D, substantially as set forth.

In testimony whereof I, the said JONAH WOODRUFF, have hereunto set my hand.

JONAH WOODRUFF.
